UNITED STATES PATENT OFFICE.

WILLIAM R. WILBER, OF LOS ANGELES, CALIFORNIA

UNDERREAMER.

Application filed November 13, 1925. Serial No. 68,810.

This invention relates to under-reamers of the type employed in well drilling operations for enlarging the well bore below the lower end of a well casing, so that the latter 5 may be readily lowered into the well, and particularly pertains to improvements in under-reamers of the character set forth in United States Letters Patent No. 1,511,385, issued to me October 14, 1924.

10 Under-reamers of this type include in their ensemble a shank adapted to be lowered through a well casing on which shank is carried a plurality of cutters adapted to be advanced and retracted laterally and include 15 a mechanism whereby the cutters are automatically expanded after passing through a well casing and projected into the well bore a predetermined distance below the lower end of the well casing, and embody means 20 for locking the blades in their expanded position operable on withdrawing the shank through the well casing to release the cutters and permit them to move to their retracted 25 position and allow the tool to be drawn through the well casing. The cutter actuating mechanism embodies a spring-pressed slide bar adapted to effect a wedge action 30 on the cutters in accomplishing expansion thereof and includes slide blocks guided on 35 the shank adapted to be engaged by the well casing and operable in such manner as to shift the spring-pressed slide bar in opposition to the spring-pressure thereon in effecting freeing of the cutters, and which slide- 40 blocks and spring-pressed slide bar are so cooperatively arranged that when the spring-pressed slide-bar is retracted to effect spread or expansion of the cutters, the slide-block will be positioned to project beyond the general outer periphery of the under-reamer shank.

The present invention pertains to, and has as one of its objects the provision of, improvements in the construction and mounting 45 of the cutters whereby the latter will be securely supported by the body or shank of the reamer so as to withstand the strains imposed thereon when in their expanded and operative position.

50 The invention further pertains to the construction and mounting of the slide block with the view of simplifying the construction and insuring proper functioning thereof in effecting actuation of the cutter expanding and retracting means.

Another object is to provide an under-reamer of the above character in which the parts may be readily assembled, which is not liable to get out of order and is adapted to endure hard service.

60 With the foregoing objects in view, together with such other objects and advantages as may subsequently appear, the invention further resides in the parts, and in the combination, construction and arrangement 65 of parts hereinafter described and claimed and illustrated by way of example in the accompanying drawings, in which:

Fig. 1 is a view of the under-reamer as 70 seen in vertical section and showing it as applied with the cutters disposed in their expanded under-reaming position;

Fig. 2 is a detail in vertical section showing the cutters as disposed in their retracted position as when being lowered or with- 75 drawn through a well casing;

Fig. 3 is a perspective view of one of the slide blocks;

Figs. 4 and 5 are fragmentary views in vertical section showing one of the slide 80 blocks in its uppermost and lowermost positions respectively;

Fig. 6 is a detail in horizontal section as seen on the line 6—6 of Fig. 1;

Fig. 7 is a view in horizontal section as 85 seen on the line 7—7 of Fig. 1;

Fig. 8 is an enlarged horizontal section as seen on the line 8—8 of Fig. 1;

Fig. 9 is an end view of the under-reamer with the cutters advanced as shown in 90 Fig. 1;

Fig. 10 is a perspective view of the under-reamer;

Fig. 11 is a detail in section and elevation illustrating the manner of forming and 95 mounting the cutters, and showing the parts as positioned to dispose the cutters in their advanced position; the view showing one of the cutters removed;

Fig. 12 is a view in section and elevation 100 illustrating a cutter as disposed in its retracted position;

Fig. 13 is a view in side elevation, partly in vertical section, of the lower end portion of the under-reamer as viewed looking 105 toward the cutter;

Fig. 14 is a perspective view of one of the cutters as seen from the rear side thereof; and

Fig. 15 is a perspective view of the lower 110

end portion of the slide-bar employed in effecting spread or expansion movement of the cutter.

Referring to the drawings more specifically, 16 represents the shank or body member of the reamer which is of tubular cylindrical form and is of such diameter that when inserted in a well casing, indicated at 17, the outer periphery of the shank will be 10 spaced slightly from the inner surface of the well casing to afford a clearance. The lower end of the shank 16 is formed with a transverse slot opening to the lower end of the shank, the side walls of which slot are 15 formed with opposed vertically extending recesses 18, as shown in Figs. 8, and 11, and are also formed with depressions 19 and 20 having outer marginal walls 21 which incline outwardly and downwardly and constitute shoulders that serve as abutments for 20 limiting outward movement of cutters A and B; the lower margins of the recesses 21 being arcuate and serving as ledges on which the cutters A and B are supported through the 25 medium of laterally projecting side flanges C and D formed on the cutters; the lower ends of the flanges normally seating on the end walls 22 and being adapted to abut against the inclined walls 21 to limit outward 30 movement of the cutters. The upper ends of the cutters A and B are designed to seat on the upper end of the slot in the shank so as to abut upwardly against the shank when the cutters are in their outermost or expand- 35 ed positions, as shown in Fig. 11.

In order that the cutters may be positioned in the slot with the flanges C and D thereon extending into the recesses 19 and 20, the recesses 18 open to the lower end of the shank 40 between the ledges, 22, as shown in Fig. 11, so that the flanges C and D may be passed through the recesses 18 and brought into position in the recesses 19 and 20, as in assembling the cutters, and also to permit removal of the cutters. The lower ends of the 45 cutters are provided with cutting heads E, the outer faces of which are curved on the arc of a circle whose diameter is equal to the diameter of the hole to be reamed. The 50 lower faces F of the cutters are flat and incline upwardly and inwardly from the outer to the inner faces of the cutters. The cutters are of such length that when their upper ends are seated on the shank the cutter heads E will depend below the lower end of the shank and are of such width as to slidably 55 conform to the side walls of the end slot in the shank and are of such lateral breadth that when the cutters are disposed 60 in their retracted positions, as shown in Fig. 2, their outer faces will lie substantially within the boundary of a circle whose diameter is less than the internal diameter of the well casing.

65 Arranged in the tubular bore 23 of the

shank 16 is a slide-bar 24 which is formed with a reduced upper end portion, as indicated at 25, around which is wound a coil spring 26, the upper end of which spring bears against a collar 27 formed on the slide-bar and the lower end of which bears on a key 28 extending through a slot 29 formed in the slide-bar; the key 28 having its end portions projecting into opposed slots 30 formed in the shank 16 and through which slots the key may be readily removed and replaced. The key 28 is normally held in a seated position against the bottom walls of the slots 30 under the action of the spring 26 and is held against longitudinal displacement by means of a lug 31 on the key projecting downwardly into the bore 23. The slots 30 are of such vertical width as to permit the key 28 with its lug 31 being passed therethrough either in putting the key in 35 place or removing it. Spaced downwardly from the key 28 is a second key 32 which passes through a transverse slot 33 formed in the slide bar and also extends into opposed slots 34 in the shank 16 through which the key 32 may be readily removed and replaced. An upwardly extending lug 35 on the key 32 projects into the bore 23 to engage the walls of the latter whereby the key 32 is normally held against longitudinal displacement. The 40 outer end portions of the key 32 project into the field of side recesses 37 on the shank, the side walls of which recesses are formed with inturned flanges 38 on their opposite outer marginal edges forming guideways. The 45 slide blocks G are mounted in these guideways, the formation of which slide blocks is particularly shown in Fig. 3; the slide blocks including oppositely extending side flanges H and I which project into the guideways and underlie the flanges 38 whereby the slide blocks are held in place within the guideways. The slide blocks are each formed with inturned end portions J and K and are beveled at the intersection of their upper and lower end faces with their outer faces, as indicated at L and M. The upper faces of the 50 projections J and K are also beveled, as indicated at N and O.

The slide blocks normally gravitate to a 55 position with their lower ends seating on the outwardly projecting end portions of the key 32 and are adapted to move vertically in their guideways to effect downward movement of the slide-bar or under the influence 60 of upward movement of the slide-bar, as occasion may be, and as will be later described.

When the slide bar is disposed in its 65 lowermost position, as shown in Fig. 2, the slide blocks G seating on the key 32 will be 70 disposed in an innermost position with the inturned end portions J and K thereon projecting into transverse slots P and Q formed in the shank, as shown in Fig. 5. The upper 75 walls of the slots P and Q are inclined out- 80

wardly and upwardly, as indicated at R and S, respectively, and the upper faces of the projections J and K on the slide-block are likewise inclined so that upward pressure imparted to the slide-blocks when in their lowermost position, as shown in Fig. 5, will cause these blocks to ride out of the slots P and Q so that the slide blocks may move vertically with the slide-bar into the position shown in Fig. 4, with the projections J and K on the slide-block seating on the shank and with their outer portions projecting beyond the boundaries of a circle having a diameter corresponding to the internal diameter of the well casing whereby after passing the tool shank through the well casing a sufficient distance to dispose the slide-blocks beneath the lower end of the casing with the slide-blocks disposed in their outermost positions, the latter will be engaged by the lower end of the casing on the lifting of the tool shank so as to cause the slide-blocks to move downwardly in their guideways and thereby cause them to act through the key 32 to advance the slide-bar 24 downwardly in opposition to the spring 26.

As a means for facilitating mounting and demounting of the slide blocks the recesses 37 are continued above the inturned flanges 38 such distance as to permit the slide blocks being disposed in the recesses and then moved downwardly therein to bring the side flanges of the slide blocks beneath the in-turned flanges 38. After thus positioning the slide blocks in the guideways the extended portions of the recesses are filled by removable plates 40 secured in place by screws 41, the lower ends of which plates extend adjacent to the guideways and serve to limit upward movement of the slide blocks.

The lower end of the slide bar 24 extends between the cutters A and B and terminates in a head 41 which projects beneath the cutters so that it may enter the bore in advance of the cutters and serve to assist in guiding and centering the cutters as the tool advances; the head 41 being preferably formed with its lower end portions substantially wedge-shaped as shown in Fig. 15. The head 41 is enlarged with relation to the slide-bar on which it is carried, and is formed with transversely extending shoulders 42 projecting from opposite sides of the slide bar, which shoulders are adapted to abut against the lower end of the shank 16 when the slide-bar is disposed in its uppermost position, as particularly shown in Figs. 1 and 11, and projecting upwardly from the shoulders 42 are dove-tailed extensions 43 which slidably engage channels 44 formed in the shank 16, which extensions serve to hold the lower end portion of the slide-bar against lateral displacement.

Formed at the intersection of the head 41 with the slide-bar 24 are inclined ledges 45 leading downwardly from opposite sides of the slide-bar on which the lower inclined ends of the cutters are adapted to seat when the slide-bar is in its lowermost position, as shown in Figs. 2 and 12, and which inclined ledges serve in cooperation with the inclined ends of the cutters as a means for effecting spreading of the cutters at their lower ends on upward movement of the slide-bar. The ledges 45 extend downwardly toward the inclined or tapered sides of the head and meet beveled faces 45' which intersect the side faces of the head.

Formed on opposite sides of the slide-bar, a short distance above the inclined ledges 45 are oppositely extending inclined protuberances 46 which, when the slide-bar is in its lowermost position, project into recesses 47 formed on the inner faces of the cutters, and which protuberances operate to spread the upper end portions of the cutters when the slide-bar is in its uppermost position, thus co-acting with the inclined ledges 45 in shifting the cutters outwardly in relation to each other to their expanded positions at both their upper and lower ends; the protuberances 46 and the inclined ledges 45 being so proportioned in relation to the transverse widths of the recesses 19 and 20 on the shank and the shoulders C and D on the cutters that when the slide-bar is in its uppermost position the cutters will be moved outwardly to a position with the flanges C and D abutting against the shoulders 21 with the upper inner end portions of the cutters abutting against the protuberances 46 and with the lower end portions of the cutters seating on the beveled faces 45' at the sides of the head 41 as particularly shown in Figs. 1 and 11, thus securely holding the cutters against inward movement when in their expanded and cutting position.

Formed on opposite sides of the cutters are shoulders 48 which project beneath the lower end of the shank and serve in cooperation with the abutment of the upper ends of the cutters against the shank in transmitting end thrusts on the cutters directly to the shank.

In assembling the underreamer, the cutters A and B are first put in place as before described, and the slide-bar 24 with the spring 26 thereon is inserted in the bore 23 of the shank 16 from the lower end of the latter and advanced to nearly its uppermost position relative to the shank, whereupon the key 32 is put in place through the slots 34 in the shank, and key 28 is then put in position through the slots 30; the spring 26 being engaged by a suitable tool and held in retracted position during placement of the key 28. On release of the spring the latter

will bear on the key 28 and will then act to maintain the slide-bar in its uppermost position. The slide blocks are then disposed in their guideways as before described, thus completing assemblage of the tool.

In the application and operation of the invention, the reamer is affixed to the usual drill stem in an ordinary manner and preparatory to its being passed through the well casing 17, the slide bar is drawn forward under opposition of the spring 26 so that the cutters A and B may be disposed in their retracted positions, as shown in Fig. 2, whereupon the slide blocks are positioned so that their lower ends will abut on the key 32 with their inturned end portions extending into the slots P and Q formed in the shank. The reamer may now be inserted in the well casing and passed therethrough; the slide blocks being held in place in the slots P and Q by the well casing until the reamer is lowered to a position below the lower end of the casing, whereupon on the slide-blocks being relieved by the casing the spring 26 will urge the slide-bar 24 upwardly thereby causing the slide blocks to ride out of the slots P and Q into the position shown in Fig. 4; the slide-bar in moving upwardly under the urge of the spring also acting to effect expansion of the cutters through the medium of the inclined ledges 45 and the protuberances 46 whereby the cutters are disposed in their outermost under-reaming position, as before described.

It is to be noted that when the cutters are in their expanded positions their upper ends will seat directly on the shank and the shoulders on the cutter heads will bear on the lower end of the shank to oppose end thrust of the cutters, and their upper inner portions will bear directly on the slide-bar, while the lower ends of the cutters will seat on the sides of the head 41 thus opposing any inward movement of the cutters by thrust imposed thereon during their underreaming operations.

It will be seen that the upper portions of the cutters in bearing directly on the slide-bar from opposite sides thereof will oppose each other, so that a thrust imposed on the blades directed toward the center of the shank will be transmitted to the opposite cutter and thence to the shank through the flanges C and D; outward movement of the cutters being limited by reason of the abutment of the flanges C and D against the shoulders 21 on the shank. When the parts are thus positioned the cutting edges of the under-reamer cutter will be disposed so as to ream the well bore of a diameter to accommodate the well casing.

When it is desired to remove the reamer it is drawn upwardly into the casing, which

upward movement causes the slide blocks to be engaged by the lower end of the casing and to be momentarily held during continued upward movement of the reamer shank relative thereto, until the slots P and Q in the shank are brought opposite the in-turned ends of the slide block, whereupon the latter moves inwardly so as to pass into the casing. This relative movement of the slide blocks and shank effects a relative downward movement of the slide-bar so as to dispose the head 41 and the protuberances 46 out of their spreading engagement with the cutters so that as the reamer is drawn upwardly into the casing, the latter will engage the outer face of the cutters and act to shove the latter inwardly into their retracted positions.

While I have shown and described a specific embodiment of my invention, I do not limit myself to the exact details of construction and the arrangement shown, but may employ such changes and modifications as may come within the spirit of the invention as defined in the following claims.

I claim:

1. In an under-reamer, a shank formed with a transverse slot, a pair of cutters arranged in said slot and slidably supported therein, a slide-bar carried by said shank and interposed between said cutters, oppositely inclined ledges on said slide-bar adapted to engage the lower end portions of said cutters, protuberances on said slide-bar engageable with the upper end portions of said cutters, said ledges and protuberances operable on longitudinal movement of said slide-bar to move the cutters outwardly at their upper and lower ends, and means for limiting outward movement of the cutters.

2. In an under-reamer, a shank formed with a central bore, a slide-bar extending through said bore and projecting through the lower end of said shank, a head on said slide-bar adapted to abut against the lower end of the shank when said slide-bar is in its uppermost position, a pair of dove-tailed extensions on said head slidably engaging the side channels on said shank, oppositely inclined ledges at the intersection of the head and shank, a pair of cutters slidably supported by said shank adapted to be positioned with their lower ends seating on said ledges, and means on said slide-bar cooperating with said ledges to effect expansion of said cutters.

3. In an under-reamer, a shank formed with a central bore and having a transverse slot opening at its sides and lower end, the side walls of which slot are formed with recesses having arcuate shoulders forming their lower margins, a pair of cutters arranged in said slot, flanges on said cutters extending into said recesses and seating on said shoulders, a slide-bar arranged in the

bore in said shank having oppositely inclined ledges arranged to engage the lower ends of said cutters and operable to effect spreading of the lower end portions of the cutters on upward movement of the slide-bar, protuberances on said slide-bar operable to effect spreading of the upper end portions of said cutters on upward movement of said slide-bar, and shoulders on

5 said shank cooperating with said flanges to limit outward movement of said cutters.

4. In an under-reamer, a shank formed with a central bore and having a transverse slot at its lower end, a pair of cutters slidably supported in said slot, a slide-bar reciprocably mounted in the shank bore, spring means for advancing said slide-bar in an upward direction, means operable on upward movement of said slide-bar for effecting expansion of said cutters, a trans-

verse key carried by said slide-bar projecting through side openings in said shank, a pair of slide blocks carried on the sides of said shank, guideways on the shank in which said blocks are slidable longitudinally of the shank, spaced inturned projections on said slide blocks adapted to seat on the bottom of their guiding channels whereby the outer portions of said slide blocks protrude beyond the peripheral face 25 of the shank, said slide-blocks being adapted to seat on the projecting ends of said key, and means whereby said slide-blocks may be moved inwardly toward the axis of the shank when said slide-bar and its key are 30 disposed in a lowermost position.

In testimony whereof, I have affixed my signature.

WILLIAM R. WILBER.
